[57] CLAIM

The ornamental design for a chest of drawers, as shown and described.

DESCRIPTION

FIG. 1 is a front perspective view of a chest of drawers showing my new design;

FIG. 2 is a top plan view thereof;

FIG. 3 is a front elevational view thereof;

FIG. 4 is a right side elevational view, the left side being a mirror image thereof;

FIG. 5 is an enlarged fragmentary cross sectional view taken along line 5—5 of FIG. 3;

FIG. 6 is an enlarged fragmentary cross sectional view taken along line 6—6 of FIG. 3;

FIG. 7 is a front perspective view of a second embodiment of the chest of drawers shown in FIG. 1;

FIG. 8 is a top plan view thereof;

FIG. 9 is a front elevational view thereof;

FIG. 10 is a right side elevational view, the left side being a mirror image thereof;

FIG. 11 is an enlarged fragmentary cross sectional view taken along line 11—11 of FIG. 9;

FIG. 12 is an enlarged fragmentary cross sectional view taken along line 12—12 of FIG. 9;

FIG. 13 is a front perspective view of a third embodiment of the chest of drawers shown in FIG. 1;

FIG. 14 is a top plan view thereof;

FIG. 15 is a front elevational view thereof;

FIG. 16 is a right side elevational view thereof;

FIG. 17 is an enlarged fragmentary cross sectional view taken along line 17—17 of FIG. 15; and,

FIG. 18 is an enlarged fragmentary cross sectional view taken along line 18—18 of FIG. 15.

The bottom and rear of all the embodiments form no part of the claimed design.
